UNITED STATES PATENT OFFICE.

JAMES ROBERTSON, JR., OF WEEHAWKEN, NEW JERSEY.

REPAIR-PATCH FOR RUBBER FOOTWEAR.

15,201.

Specification of Reissued Letters Patent. Reissued Sept. 20, 1921.

Original No. 1,354,846, dated October 5, 1920, Serial No. 374,519, filed April 17, 1920. Application for reissue filed February 10, 1921. Serial No. 444,054.

To all whom it may concern:

Be it known that I, JAMES ROBERTSON, Jr., a citizen of the United States of America, residing at Weehawken, county of Hudson, 5 and State of New Jersey, have invented new and useful Improvements in Repair-Patches for Rubber Footwear, of which the following is a specification.

This invention relates particularly to a 10 repair patch applicable to the toe or heel of a rubber or overshoe, and the object is to provide a patch of such form that it may be applied to either the toe or heel, and to a considerable range of models and sizes so 15 that the repair man is under the necessity of having in hand only a limited number of different sizes of repair patches in order to be prepared to repair any size or model of rubber or overshoe that may be offered. A 20 further object is to provide a form of repair patch that may be applied expeditiously and in a substantial and workmanlike manner.

In the accompanying sheet of drawings which forms a part of this application—

25 Figure 1 is a top view of a repair patch according to this invention.

Fig. 2 is a side view of the same.

Fig. 3 is a section on the line III—III of Figs. 1 and 2.

30 Fig. 4 shows a patch applied to both the heel and toe of a rubber, the patch being in section on the line IV—IV of Figs. 1 and 3.

The repair patch is preferably a single 35 molded piece of rubber and comprises a heavy tread portion 5 with a thickness, for example, of from an eighth to three-sixteenths of an inch so as to stand considerable wear. This thickness is such that it is comparatively inelastic. This portion is rounded at one end and is of sufficient area to 40 cover all of the heel or as much of the sole as it is desired to cover. Upstanding from the rounded end of the tread portion is a flange 6 which curves over the tread portion. The 45 flange at the bottom margins 7, 7 of its ends is sharply incurved and joins to the tread portion at a distance from the margin of the tread portion. In consequence of the manner of joining the repair patch can be 50 fitted to a rubber or overshoe which has a heel or toe with a width equal to the distance between the points of joining of the incurved margins with the tread portion, or which has a greater width, and the flange 55 can be bent into contact with the sides of the

rubber when it is narrow, or, when the heel or sole is wide the incurved bottom margin may be rolled out to accommodate the greater width. When applied at the heel the upper edge of the flange will be somewhat stretched and the flange bent back. When applied at the toe the flange may need to be curved somewhat more than its normal form.

By reason of the flange being curved over 60 the tread portion and also being thin, flexible and elastic it can be turned inside out and rolled under the tread, and when this is done it will not spring back of its own accord.

In preparation for applying, the flange is first turned under the tread and cement is applied to all of the surfaces of the repair patch and of the rubber or overshoe which are to come together and the cement allowed 70 to dry. The tread is then applied to the heel or sole with the flange still rolled back and after applying the flange is rolled up into place. After applying any portions of the tread which project beyond the heel or sole 75 are trimmed off.

I find that because the material of the flange is thin, flexible and elastic, the incurve at the bottom margins 7, 7, though desirable, is not essential. Therefore I do not wish to 80 limit myself by the inclusion of this feature in the broader claims.

What I claim as new, and desire to secure by Letters Patent of the United States, is—

1. A repair patch for footwear comprising 90 a tread portion rounded at one end and having a flexible and elastic flange upstanding from the rounded end of the tread portion and having the bottom margins at its ends joined to the tread portion at a distance from 95 the margin of the tread portion and sufficiently thin and flexible to have a bending line at its juncture with the tread portion whereby the flange can be brought into contact with the sides of the footwear when it is 100 narrow and may be brought into contact with the projecting margins of the tread portion to accommodate wider footwear, substantially as described.

2. A repair patch for footwear comprising 105 a tread portion rounded at one end and having a flexible and elastic flange upstanding from the rounded end of the tread portion and having the bottom margins at its ends incurved and joined to the tread portion at 110

a distance from the margin of the tread portion, substantially as described.

3. A repair patch for footwear comprising a tread portion rounded at one end and having a flexible and elastic flange upstanding from the rounded end of the tread portion and curved over the tread portion and

having the bottom margins at its ends in-curved and joined to the tread portion at a distance from the margin of the tread portion, substantially as described. 10

Signed at New York, N. Y., this ninth day of February, 1921.

JAMES ROBERTSON, JR.
